(No Model.)

S. D. FIELD.

TELEGRAPHY.

No. 392,914.

Patented Nov. 13, 1888.

Fig. 1.

UNITED STATES PATENT OFFICE.

STEPHEN DUDLEY FIELD, OF STOCKBRIDGE, MASSACHUSETTS.

TELEGRAPHY.

SPECIFICATION forming part of Letters Patent No. 392,914, dated November 13, 1888.

Application filed August 24, 1888. Serial No. 283,641. (No model.)

To all whom it may concern:

Be it known that I, STEPHEN DUDLEY FIELD, a citizen of the United States, residing at Stockbridge, in the county of Berkshire and State of Massachusetts, have invented certain new and useful Improvements in Telegraph Systems; and I do hereby declare the following to be a full, clear, and exact description of the invention, such as will enable others skilled in the art to which it appertains to make and use the same.

This invention relates to a novel system of telegraphy, which I have termed a "diplex telegraph," but which, as will be seen, is capable of being duplexed in any manner well known in the art to form a quadruplex system, or may be combined with any of the well-known methods of transforming a duplex system into a sextuplex or multiplex system.

20 The invention comprises a novel form of transmitting apparatus and a novel form of receiving apparatus adapted thereto; and it consists in the arrangement and combination of devices and instrumentalities, substantially as hereinafter more fully described and claimed.

In the accompanying drawings, which form part of this specification, Figure 1 is a diagram illustrating the entire system of transmitting apparatus, line, and receiving apparatus in one of the simple forms of the invention. Fig. 2 is a transverse view of the supplementary tongue or arm of the relay of the receiving apparatus alone.

In carrying out my said invention I propose 35 to use three dynamo-electric generators so arranged that two of them will be adapted to send current of one kind over the line with the electro-motive force of one alone or that of the two combined in series, while the third 40 dynamo is arranged to be connected into line, so as to send a current the reverse as to direction compared with the two former machines; and I use a single key and a double key in order to give perfect facility to two operators 45 to operate their keys in a manner totally independent of each other. The receiving apparatus is designed to operate in such manner that when either of the transmitting keys is operated a corresponding local sounder at the 50 receiving end will be actuated according to

which of the two keys is worked at the moment, and when both keys happen to be worked simultaneously then both the local sounders at the receiving end will give the signals correspondingly.

55

To these ends my invention is as follows:

First, as to the transmitting apparatus, I use two keys, both of the continuity-preserving type, one being a single key and the other a double key. The single key K' is formed 60 so as to normally close the contacts 1 and 2 and have the contacts 3 and 4 open, and by pressing the knob of the key the contacts 3 and 4 are closed, while the contacts 1 and 2 are opened. The double key K² is formed on one 65 leg with a similar set of contacts, of which 5 and 6 are closed when the key is idle and contacts 7 and 8 are opened; but by operating the knob of the key the contacts 7 and 8 are closed and the contacts 5 and 6 are opened, while a 70 similar set of contacts on the other leg are arranged so that when the key is idle the contacts 9 and 10 are open and the contacts 11 and 12 are closed; but when the key-knob is depressed contacts 9 and 10 become closed, while 75 contacts 11 and 12 are simultaneously opened.

The circuits are as follows: The line comes to the contacts 1 and 3 of key K'. From contact 2 a local circuit is established with the contacts 10 and 12, and includes a fixed resistance, R'—for example, one hundred ohms. From the key K' a circuit is run to the positive pole of the shunt-wound dynamo-electric machine D' and a fixed resistance, R², again inserted, (in the instance given one hundred 85 ohms.) From the negative pole of the dynamo D' a circuit is carried to the contacts 5 and 7; but from the key K², and therefore contact 8, a circuit is carried to the positive pole of a second shunt-wound dynamo-electric machine, 90 D², and from the negative of the same machine a circuit is carried direct to earth. Earth-circuits are also established from contacts 6 and 11, and included in each of said circuits is a fixed resistance of, say, two hundred ohms, 95 and marked, respectively, R³ and R⁴, and such earth-circuits are, for convenience, shown as being joined to the earth-circuit of dynamo D'. From the second arm of the key K², and therefore from its contact 9, a circuit is established 100

to the negative pole of the dynamo D^3 , such circuit including a fixed resistance, R^5 , of, say, one hundred ohms, and the positive pole of such dynamo D^3 is connected direct to earth 5 along with the other earth-circuits. Of course, if desired, each of the foregoing earth-circuits may be established independently; but such is unnecessary. Upon now following out the operations of the two keys it will be seen that in 10 their normal position, as shown in Fig. 1, the circuits of respective dynamos are all open. On depressing the key K' , contacts 1 and 2 are broken and contacts 3 and 4 are closed. This immediately sends an impulse of positive current 15 over the line, which returns by way of ground through resistance R^3 , contacts 6 and 5, and the negative pole of the dynamo D' , supposing at the moment that the key K^2 is idle. If, on the other hand, key K^2 happens to be depressed 20 at the same instant, the contacts 7 and 8 are closed and contacts 5 and 6 are opened. Therefore the dynamos D' and D^2 are thrown into series, and, starting from the positive pole of D^2 , the current goes to contacts 8 and 7, 25 negative pole of the dynamo D' , positive pole of the same, resistance R^2 , contacts 4 and 3, and thence to line, returning by way of ground direct to the negative pole of dynamo D^2 . We have therefore the condition that if key K' is 30 depressed alone (the dynamos all being of substantially the same potential—say one hundred volts each) a positive current of one hundred volts is sent over the line, and if it happens that key K^2 is depressed at same time a 35 positive current of two hundred volts is sent over the line. On the other hand, if while key K' is idle key K^2 is depressed, neither of the dynamos D' or D^2 has a closed circuit, and are therefore inoperative; but dynamo D^3 will operate 40 through resistance R^5 , contacts 9 and 10, resistance R' , contacts 2 and 1, to line, sending a negative current of one hundred volts, and the positive pole of said dynamo D^3 is closed to the return earth. We have therefore three 45 conditions, viz: key K' alone operating, sending a particular current over the line, or key K^2 alone operating and sending a different character of current over the line, or, finally, both keys operating together, in which an entirely 50 different current is sent upon the line, so as to actuate both receiving-instruments.

The various fixed resistances above alluded to are located as named for the purpose of equalizing the electrical resistances of various 55 circuits under the conditions on which they are operated in carrying out the invention. Taking the figures given above, then we have on the depression of the key K' one hundred volts positive in line when key K^2 is idle or 60 up, and on the depression of key K^2 , when key K' is idle or up, a current of one hundred volts negative in line, and when both keys are depressed at same time we have two hundred volts positive in line. It now remains to obtain 65 an apparatus which will select these different currents in such manner as to receive the signals in the manner in which they are

sent. For this purpose I construct a receiving-relay as follows:

M represents a tubular magnet having the 70 adjustable core C , provided with thumb-nut N , by which means the core may be readily introduced or withdrawn to any desired extent. The edge of the walls of the magnet M is slotted at diametrical points for the reception 75 of the tongue c , which carries a coil of fine wire, a , and is pivoted below in a suitable manner. A similar tongue, d , is independently pivoted and carries a coil, b , of fine wire of such diameter as to easily fit over the coil a . The 80 two tongues are so situated relatively that their coils a and b are substantially in the same plane, and both to a greater or less extent surround the projecting end of the core C of the magnet M , and they therefore occupy a 85 position directly in the lines of force which pass from the core C to the external walls of the magnet. This field of force is rendered very intense by the form of the magnet M and the use of as large a current as may be found 90 necessary, supplied by a local battery, B^3 .

The coils a and b are differentially connected in series, so that current passing through the coil a will pass through coil b in a reverse direction, so that the tendency of the coils a and b , when energized by a sufficient current from the line, is to cause the tongues c and d to separate from their normal position or approach more closely together. The line comes in to 95 one of the coils—say a —passes thence to the other coil, and from it goes to ground, as shown.

The local circuits of the relay are as follows: Tongue d carries a contact, 13, which in normal position is closed against contact 14, 105 which is fixed in any suitable manner on the base of the relay, and from contact 14 a circuit is carried around to a pivoted arm, e , whose pivotal axis is vertical. The tongue d is drawn against the contact 14 by means of the spring 110 g , which is adjusted by the adjusting-screw i , suitably arranged. The tongue c carries a contact, 15, which is normally closed on a contact, 16, carried by the arm e , and these contacts 15 and 16 are independently maintained in 115 closed relation by an isolated spring, f . At the outer extremity of the arm e , which is shown onlapping over the tongues c and d , is a contact, 18, which is closed normally against a fixed contact, 17, by means of the spring h , 120 adjusted by a suitable adjusting-screw, j . A circuit is run from the tongue d through a local battery, $L B'$, and a sounder, S' , thence around to a fixed contact, 17. Another local circuit is run from a tongue, c , through a local battery, 125 $L D^2$, a sounder, S^2 , and thence likewise around to the fixed contact 17.

Thus constructed the operation of the receiving apparatus will be as follows: The polarity of the magnet M will be so arranged 130 with relation to the different currents that the tongues c and d will be drawn toward each other by negative line-current and will be repelled from one another by a positive line-current of

normal potential. When the key K' is depressed, sending one hundred volts positive into line, contacts 13 and 14 separate by reason of repulsion of the coil b , and this makes the 5 corresponding signal on the local sounder S' . When the key K'' is depressed, contacts 15 and 16 separate by reason of repulsion by the magnet M of the coil a , and this opens the circuit of the local sounder S'' , and the signal is 10 distinguishable. When both keys K' and K'' are depressed together, (which occurs when each of the operators desires to send an impulse over the line at the same instant,) the resulting double current of two hundred volts 15 positive is sufficient to overcome the spring h , and the contacts 17 and 18 are separated by the increased attraction of the magnet M for coil a , and therefore the two local-sounder circuits are opened and the signal is distinguished 20 by each of the receiving operators. Therefore all necessary requirements are observed, and the system is completely practical with the devices I have shown above.

Of course it is obvious that the mere form is 25 not essential to the success of the invention, and the same may be varied to any desired extent without departing from the spirit of my invention.

It will be observed that the spring f is not 30 attached to any fixed adjusting-screw, but is self-contained between the tongues c and the arm e , and therefore it of itself has no tendency to affect the solidity of contact between the points 17 and 18, which would be the case 35 if it were attached to any fixed point instead of to the arm c .

It will also be observed that the adjustment of magnetic field for the coils a and b lies entirely in the construction of the magnet itself; 40 and I therefore in this instance do away with a series of resistances in the circuit of the energizing-battery.

I claim as my invention—

1. In a system of telegraphy, a transmitting 45 apparatus comprising, in combination with a line and earth, the armatures of three shunt-wound dynamo-electric generators, two continuity-preserving keys located between said armatures and the line, and fixed resistances 50 located between each of said armatures and earth, substantially as described, whereby said armatures are adapted two of them to send

impulses independently or jointly, and the third independently only.

2. A telegraph-relay comprising two or 55 more nested coils suspended in and inductively energized by a common field of force and provided with levers and contact-points for the local circuits, substantially as described.

3. A telegraph-relay comprising two coils 60 differentially included in the line and suspended in substantially the same plane in an annular field of force and provided with levers and contact-points.

4. The described triple-contact relay, consisting, in combination with two sounder-circuits and their batteries, of two coils differentially connected in series and suspended in a magnetic field, two pivoted tongues carrying said coils, and a third tongue or arm so 70 arranged with contacts in three pairs, substantially as described, that a given current in one direction will separate one pair, the same current in the opposite direction will separate another pair, and a stronger current in the 75 first direction will separate a pair forming a part of both the other circuits.

5. A telegraph-relay having as its sensitive part two differentially-connected coils and three pairs of local-circuit contacts, one pair of 80 which forms a path for each of the remaining pairs, in combination with two local-sounder circuits, and means for communicating the movements of said coils to the respective pairs of contacts.

6. In a telegraph-relay, the combination of the pivoted tongues c d , supporting the coils a b in a magnetic field, and having the contacts 13 and 15, the fixed contacts 14 and 17, and the transverse arm e , having contacts 16 90 and 18, substantially as described.

7. In a telegraph-relay having a vibrating or pivoted tongue, c , provided with a contact, 15, the combination therewith of a pivoted tongue or arm, e , having a contact, 16, and an insulated spring, f , adapted to normally hold said contacts together, while permitting a limited movement to both tongue c and arm e .

In testimony whereof I affix my signature in presence of two witnesses.

STEPHEN DUDLEY FIELD.
